UNITED STATES PATENT OFFICE.

MAUDE MINER, OF LOS ANGELES, CALIFORNIA.

ABDOMINAL BAND.

Application filed January 23, 1922. Serial No. 531,188.

To all whom it may concern:

Be it known that I, MAUDE MINER, a citizen of the United States, residing at Los Angeles, in the county of Los Angeles and 5 State of California, have invented a new and useful Abdominal Band, of which the following is a specification.

This invention relates to abdominal bands of the character employed, for example, on 10 the bodies of newly born infants for the purpose of preventing umbilical-hernia.

An object of the invention is to produce a band of this character that will snugly fit about the body of the infant in contact with 15 and supporting every portion of the abdominal region.

Another object is to prevent wrinkling and bunching of the band so that it will not irritate the baby's body.

20 Another object is to provide for ease of placing the band on and removing it from the baby, even though done by inexperienced mothers.

Another object is to provide a band constructed so that the baby need be turned over but once in applying the band to its body. With bands now in use it is necessary to turn over the infant twice.

Another object is to facilitate fastening 25 of the band in place, and this is effected by a construction permitting both ends of the band being secured on the outerside.

The accompanying drawings illustrate 30 one embodiment of the invention.

35 Fig. 1 is a plan view of an abdominal band constructed in accordance with the provisions of this invention, said band being opened out flat so that its construction can be clearly seen.

40 Fig. 2 is a perspective view of the band as it would appear closed on the body of an infant.

In the drawings there is shown a strip of 45 woven or knitted fabric comprising end wider portions 3, 4, respectively, and an intermediate narrower portion 5. The portion 3 is longer than the portion 4 and is constructed of three separate pieces indicated at 50 *a*, *b* and *c* respectively. The piece *a* also includes the portions 4 and 5. The pieces *a* and *c* have their weft threads extending longitudinally of the band to prevent stretching lengthwise, and the piece *b* has its weft threads extending transversely of 55 the band. The piece *b* is provided longitudinally thereof with a slit 6 of a length

equal to the width of the portion 5 so that when the end portion 4 is slipped through the slit 6, the portion 5 will lie smoothly within the slit.

The opposite ends of the band are rounded, as indicated at 7, and any suitable fastening means may be attached to the band for securing it about the body of an infant. In the particular instance shown in the 65 drawings a single tape 8 is secured medially of the portion 4, and a single tape 9 is secured at one end substantially medially of the piece *c*.

To apply the band to the infant the 70 infant will be laid on its back upon that part of the portion 3 extending between the slit 6 and the portion 5. Then the portion 4 will be brought around over the infant's body and passed through the slit 6 and 75 drawn snugly about the body of the infant. Then the portion *c* will be folded over the portion 5. The infant will then be rolled over on its face, thus bringing the opposite ends of the band at one side of the infant's 80 body. The tapes 8, 9, will then be tied together so as to secure the band in place. If desired, the tapes 8, 9, may be omitted and a safety pin employed for securing the ends of the band together.

85 From the foregoing it will be clear that the inner face of the band, when in place upon the infant, is perfectly smooth with the exception of the overlapping of one edge of the slit 6 upon the portion 5. This overlapping, however, comes at the side of the infant and can therefore do no harm.

I claim:

1. In an abdominal band, a strip of fabric having wider end portions and a narrower 95 intermediate portion, one of the wider portions having a transverse slit of a length equal to the width of the narrower portion.

2. In an abdominal band, a strip of fabric having wider end portions and a narrower 100 intermediate portion, one of the wider portions having a transverse slit of a length equal to the width of the narrower portion, and fastening tapes secured at one end along the median line of the strip.

3. In an abdominal band, a strip of fabric having a wider end portion and a narrower portion, the wider portion having a transverse slit of a length equal to the width of the narrower portion, the wider portion being formed from three pieces of fabric, the 110 two end pieces of the wider portion having

their weft threads extending longitudinally of the band, the intermediate piece having its weft threads extending transversely of the band, and said intermediate portion having a slit extending parallel with the weft threads thereof.

4. In an abdominal band, a strip of fabric having wider end portions of different lengths and a narrower intermediate portion, the longer wider portion having near its middle a transverse slit of a length equal

to the width of the narrower portion to enable the end of the shorter wider portion to be passed through the slit so that the ends of the band may be secured together at the ¹⁵ outer face of the band.

Signed at Los Angeles, California this 17th day of January 1922.

MAUDE MINER.
